T. M. CONGER.
RESILIENT HEEL.
FILED JAN. 28, 1921.

Inventor
T.M. Conger.

Lacey & Lacey, attorneys.

UNITED STATES PATENT OFFICE.

THOMAS M. CONGER, OF ELYRIA, OHIO.

RESILIENT HEEL.

Application filed January 28, 1921. Serial No. 440,709.

To all whom it may concern:

Be it known that I, THOMAS M. CONGER, a citizen of the United States, residing at Elyria, in the county of Lorain and State 5 of Ohio, have invented certain new and useful Improvements in Resilient Heels, of which the following is a specification.

This invention relates to elastic cushion heels and lifts and has as one of its objects 10 to provide a heel or lift which may be readily applied and secured in place, usually by a single fastening element such as a nail or screw and which when applied will not be liable to become displaced.

15 Another object of the invention is to so construct the article that the same, when in the form of a lift, will snugly fit the shoe heel and be prevented from flexing away from the heel notwithstanding the employment of but a single fastening element.

20 A further object of the invention is to provide a heel or lift so constructed that it will effectually absorb shocks and will cushion the impact of the heel with the 25 ground surface.

Another object of the invention is to provide a novel securing means for holding the lift in place upon the shoe heel and preventing the lift from turning about the securing 30 element as a pivot.

Also the invention has a further object to so form the tread face of the lift as to effectually provide against slipping on wet pavements and other slippery surfaces.

35 In the accompanying drawings:

Figure 1 is a perspective view of a heel lift constructed in accordance with the invention and viewing the tread surface of the lift;

40 Figure 2 is a similar view of the lift looking at the attaching or upper face thereof;

Figure 3 is a vertical transverse sectional view of the lift applied;

Figure 4 is a perspective view of the 45 anchoring plate employed in securing the lift to the heel of the shoe, the plate being removed from the lift;

Figure 5 is a vertical transverse sectional view on the line 5—5 of Figure 4;

50 Figure 6 is a vertical front to rear sectional view on the line 6—6 of Figure 4;

Figure 7 is a plan view illustrating a modified form of anchoring plate;

Figure 8 is a vertical front to rear sectional view on the line 8—8 of Figure 7; 55

Figure 9 is a vertical transverse sectional view on the line 9—9 of Figure 7.

In the accompanying drawings the principles of the invention are illustrated as embodied in the construction of an elastic 60 or resilient cushioning heel lift but it will be understood that the invention is not limited in this respect but may equally as well find embodiment in a heel as a unit.

In the drawings the numeral 1 indicates 65 in general the body of the lift and this body is of the usual marginal contour and, while transversely straight, is longitudinally curved throughout its length in a front to rear direction. The tread face of the body 70 is indicated by the numeral 2 and the attaching face by the numeral 3, the face 2 being convex and the face 3 concave in the initial condition of the lift although, when the lift is applied to the shoe heel, indicated 75 in the drawing by the numeral 4, the lift will be substantially flattened out by the pressure exerted by the anchoring plate which will presently be described.

In securing the lift to the shoe heel 80 I make use of an anchoring plate such as that shown in Figures 4 to 6 inclusive, or the plate shown in Figures 7 to 9 inclusive. The plate is indicated in general by the numeral 5 and the same comprises a body portion 6 85 provided centrally with an opening 7 for the passage of a securing element such for example as a nail 8 or a screw, either adapted to be driven through the lift and into the shoe heel 4. Marginally the body 6 is provided 90 with spurs certain of which are indicated by the numeral 10 and another by the numeral 11, and the plate is, in the course of manufacture of the article, embedded in the lift body 1 in such manner that the spurs 10 and 11 95 will penetrate the said body and project at their pointed entering ends 12 beyond the attaching face of the body. The series of spurs is concentric to the opening 7 in the body 6 of the plate and all of these spurs 10 100 are located in a common arc. However the spur 11 is spaced from the opening 7 preferably a greater distance than any of the spurs 10, and the securing plate is so assembled with the lift that this spur 11 will penetrate the body of the lift nearer the rear side 105

of the said body than any of the spurs 10. As stated above, the entering ends 12 of the spurs 10 and 11 project beyond the attaching face of the lift so that when the lift is 5 secured to the heel by driving the nail or other securing element 8 into place, these ends of the said spurs will also be caused to enter the heel 4, and thus, while the element 8 serves primarily as a securing means for 10 holding the lift in place upon the heel, the spurs 10 and 11 serve this purpose to a certain extent but primarily are intended to prevent rotation of the lift about the securing element 8 so that notwithstanding the 15 use of but a single securing element, the lift is securely held in place. By reference to Figures 4 and 6 it will be observed that the anchoring plate is curved continuously in the front to rear direction or in other words 20 longitudinally from that side of the body of the plate at which the spur 11 is located to the diametrically opposite side of the plate. The plate however is transversely straight as will be observed by reference to 25 Figure 5. Furthermore the plate is resilient and it will be understood that inasmuch as its curvature corresponds substantially to the curvature of the lift body in which it is embedded, the plate will serve to firmly 30 bind the attaching face of the said lift body against the shoe heel when the securing element 8 is driven into place, the anchoring plate being at such time sprung to nearly flat condition and the lift itself being likewise 35 changed in form.

In order that the attaching face of the lift may snugly seat against the lower face of the heel 4 of the shoe and in order that the lift may possess maximum efficiency as a 40 cushioning means, the said face of the lift is formed with a depression 14 bounded by a beveled upstanding marginal portion 15 extending entirely around the margin of the said face, and this face of the lift is also 45 formed in the depression 14 with an upstanding bead 16 of a height substantially equal to the raised marginal portion 12 and conforming in outline thereto, the head 16 being surrounded by the raised portion 15 50 and being designed to contact or substantially contact at its upper edge the lower face of the heel 4.

It will be observed by reference to Figure 2 of the drawings that the beveled upstanding marginal portion 15 at the opposite sides of the lift body is of gradually increasing height and width toward a point substantially midway between the front and rear ends of the lift so that when the lift 60 body is flattened out at the time of application to the shoe heel, this portion which is of increased dimensions will be stretched out or elongated and will, when the lift is entirely flattened and attached, be of substantially the same dimensions as the remaining 65

portions thereof, and thus the said upstanding marginal portion 15 will snugly contact the face of the shoe heel at all points in the length of the former.

In order to prevent slipping on wet pavements or other slippery surfaces, the tread face of the lift body may be formed with a number of flutes 17 which extend substantially radially from the central portion to the margin of the body. These flutes 17 are gradually increased in width from their inner to their outer ends, and their faces are preferably transversely concave and they are gradually increased in depth from their outer to their inner ends, as clearly shown in Figures 1 and 3 of the drawings. Also the faces of the flutes are disposed at a slight angle to the tread surface of the lift as a whole so that abrupt faces 18 are provided extending along one marginal side of the concave face of each flute. In order to further prevent slipping of the heel on slippery surfaces, it is preferable that the face 2 be formed with an upstanding rib 19 of substantially annular form which rib surrounds 90 a depression 20 and at the outer side of which the inner ends of the flutes 17 terminate.

The anchoring plate shown in Figures 7, 8 and 9 of the drawings is of the same general contour as the plate shown in Figures 4, 5 and 6 and comprises a body portion 21 corresponding to the body portion 6 and formed centrally with an opening 22 corresponding to the opening 7. Also the body 100 portion is provided at its margin with spurs 23 corresponding to the spurs 10, and a spur 24 corresponding to the spur 11. In this modified form however the body portion is preferably provided with a number of openings 25 supplemental to the opening 22 so that more than one securing nail or screw may be employed in attaching the lift to the shoe heel. Also in this modified structure it is preferable that a number of spurs 26 be stamped out from the body portion 21 in the series surrounding the opening 22, these spurs being adapted to be embedded in the heel lift at the time of manufacture, and as best shown in Figure 3 of the drawings. 110

As stated, it is preferable that the beveled marginal portion 15 of the attaching face of the lift be formed thicker at the sides of the lift than at the breast and rear of the lift so that when the lift is flattened out in applying it to a shoe heel the stretching stress to which this marginal portion is subjected, and the resultant elongation of the portion at the sides of the lift will not negative a snug engagement of the attaching face 120 against the lower side of the shoe heel.

It will be understood that the lift may be produced devoid of any anti-slipping devices upon its tread face and that therefore the illustration of the flutes 17 is intended to 130

merely disclose one manner in which the lift may be provided with anti-slipping surfaces. It will also be understood that various other changes may be made without departing from the spirit of the invention.

Having thus described the invention, what is claimed as new is:

A heel lift comprising a resilient member, an annular rib, defining a central suction area upon the tread face of said member and provided with a central aperture adapted to receive a securing element for the resilient

member; radial flutes on said tread face, said flutes extending from said rib to the margin of said member, each of said flutes having a substantially perpendicular side and a concave side connecting the base of the perpendicular side with the apex of an adjacent flute, thereby forming a sharp edge therewith, and the concave sides of all of said flutes facing in the same direction, circumferentially.

In testimony whereof I affix my signature.

THOMAS M. CONGER. [L. S.]
